8 Claims. (Cl. 230—170)

This invention relates to diaphragm pumps and has one application in sampling air for radioactive dust.

To assess the average concentration of radioactive dust to which workers are exposed, it is known practice to take samples during the working week at fixed points in the operating areas. This method can yield reliable information when the air flow pattern is well established and the source of contamination is in a fixed place, but it is sometimes necessary to determine the exposure of workers who are engaged in a number of operations or working in a variety of places. Under such conditions, air sampling at fixed points can give little indication of the true exposure.

A solution to this difficulty would be for each worker to carry a portable personal air sampler having a filter which would be examined regularly, say weekly, for radioactivity. However the high power requirements of most existing long-term samplers have made them dependent on some external power supply such as electrical mains, and therefore unsuitable for personal use.

It is an object of the present invention to provide a diaphragm pump, suitable for use in an air sampler, whose power requirements are sufficiently low to enable it to be powered by portable batteries.

According to the present invention, in a diaphragm pump the diaphragm has an aperture, an attachment member located in said aperture, said member slidably engaging a peripheral region of the diaphragm surrounding the aperture, and means for imparting to the attachment member a reciprocating movement normal to the plane of the diaphragm.

The attachment member may comprise two discs having the peripheral region located between them.

The means for imparting the reciprocating movement may comprise a connecting rod having one end connected to the attachment member, and a rotatable crank connected to the other end of the connecting rod.

To enable the nature of the present invention to be more readily understood, attention is directed, by way of example, to the accompanying drawings wherein:

FIG. 1 is a cross-sectional elevation of a diaphragm pump embodying the present invention.

FIG. 2 is an enlarged, slightly exaggerated, fragment of FIG. 1, and

FIG. 3 is a perspective cut-away view of a portable air sampler including the pump of FIG. 1.

Referring to FIGS. 1 and 2, the pump comprises a head 1 made of methyl methacrylate, having an inlet port 2 and an outlet port 3. These ports are closed by flap valves 4 and 5 respectively, consisting of pieces of aluminised polyethylene terephthalate film 0.00025 inch thick adhesively secured to the head 1. FIG. 1 shows the inlet valve 4 closed and the outlet valve 5 open.

Spaced from the head by a polyethylene ring 6 is a diaphragm 7 made of 0.004 inch polytetrafluoroethylene (PTFE) sheet. The outer periphery of the diaphragm is clamped between the ring 6 and a brass ring 12 by screws 8 (FIG. 3). In the centre of the diaphragm is a circular aperture, the peripheral region of which is engaged by an attachment member comprising a bushing 9 having a rebate which passes through the aperture and through central holes in two PTFE discs 10 and 11, 0.01 inch thick, between which the diaphragm is located. The aper-

2

ture in the diaphragm is the same diameter as the holes in the discs. The discs and diaphragm are held in the rebate by a washer 13 and bolt 14, and as the rebate is 0.032 inch long whereas the thickness of the diaphragm plus discs is 0.024 inch, the diaphragm is free to slide radially between the discs without permitting appreciable air leakage. The low-friction properties of PTFE facilitate the sliding action.

Fastened to the bushing 9 by the bolt 14 is an aluminium connecting-rod 15, in whose other end is held a low-friction bearing 16 made of a dry-bearing material. The bearing 16 is engaged by a crank pin 17 mounted eccentrically on the face of a cylindrical polyethylene block 18 fastened to the shaft of an electric motor 19 (FIG. 3). Rotation of the motor shaft thus causes the attachment member at the centre of the diaphragm to reciprocate, drawing air in through the port 2 and expelling it through the port 3. The freedom of the diaphragm to slide between the discs 10 and 11 reduces the torque required from the motor, since the reciprocation does not involve appreciable stretching of the diaphragm. This construction also strengthens the centre of the diaphragm.

In the present embodiment the diaphragm is $\frac{7}{8}$ inch in diameter and the amplitude of the reciprocation is 0.1 inch. The motor is a 6 volt constant-speed motor running at about 1700 r.p.m. from mercury type batteries.

FIG. 3 also shows the sampling head 20 which is connected to the inlet port 4 by a length of flexible tubing 21. The sampling head supports a glass-fibre filter paper or membrane filter 22 of 1.5 cm. effective diameter.

As the flow-rate remains sensibly constant during the working week, the volume of air sampled can be determined from the sampling time. This can be measured if desired by a 6 volt clock movement (not shown) operated in parallel with the pump.

The sampling head may be secured to a button-hole or attached to the worker's clothing by a safety pin. The motor/pump unit and batteries are contained in a case which is either carried in a pocket or in a pouch on a belt 40 worn round the waist.

We claim:

1. In a diaphragm pump, a diaphragm having an aperture, an attachment member located in said aperture, said member having an annular portion in interleaved slidable engagement with a peripheral region of the diaphragm surrounding the aperture, and means for imparting to the attachment member a reciprocating movement normal to the plane of the diaphragm.

2. A pump as claimed in claim 1 wherein the attachment member comprises two discs having said peripheral region located between them.

3. A pump as claimed in claim 2 wherein the means for imparting the reciprocating movement comprises a connecting rod having one end connected to the attachment member, and a rotatable crank connected to the other end of said rod.

4. An air sampler comprising a diaphragm pump including a diaphragm having an aperture, an attachment member located in said aperture, said member having an annular portion in interleaved slidable engagement with a peripheral region of the diaphragm surrounding the aperture, and means for imparting to the attachment member a reciprocating movement normal to the plane of the diaphragm.

5. An air sampler as claimed in claim 4 wherein the attachment member comprises two discs having said peripheral region located between them.

6. An air sampler as claimed in claim 5 wherein the means for imparting the reciprocating movement comprises a connecting rod having one end connected to the attachment member, and a rotatable crank connected to the other end of said rod.

7. A diaphragm pump comprising a pump head having an inlet port with a flap valve and an outlet port with a flap valve, a diaphragm having an aperture, means clamping the perimeter of said diaphragm to said pump head, an attachment member located in said aperture, said attachment member including parts spaced apart to engage the opposed surfaces of said diaphragm adjacent to said aperture, the spacing of said parts being greater than the thickness of said diaphragm, and means for imparting to the attachment member a reciprocating movement normal to the plane of the diaphragm.

8. A diaphragm pump comprising a pump head having inlet and outlet ports, a diaphragm having a central aperture, means clamping the perimeter of said diaphragm to said pump head, an attachment member located in said central aperture, said attachment member including parts

spaced apart to engage the opposed surfaces of said diaphragm adjacent to said aperture, the spacing between said parts being greater than the thickness of said diaphragm, a driver connected to said attachment member to extend normal to the plane of said diaphragm, and means to impart reciprocation to said driver to flex said diaphragm.
